UNITED STATES PATENT OFFICE

MARCEL D. KRAMER, OF NEW YORK, N. Y.

LADY'S WATCH

Application filed March 27, 1931. Serial No. 525,703.

This invention relates to timepiece ornaments, and my improvement is directed to a lady's watch having a novel form of case with means of attachment to wearing apparel, upon the breast, characterized by the face of the watch being angled in such manner that, when positioned, the wearer may read the time by merely inclining the head forwardly downward.

Other features and advantages of my invention will hereinafter appear.

In the drawing:

Figure 1 is a top plan view of my improved timepiece ornament.

Fig. 2 is an enlarged, front view thereof.

Fig. 3 is a rear view.

Fig. 4 is a side view.

Fig. 5 is an enlarged detail, in front view, of the locking means, parts being in section, and

Fig. 6 is a horizontal section, on the line 6—6 of Fig. 5.

In said views let 1 indicate a base, here shown plain, but which may bear any desired ornamentation. This base is intended to be positioned vertically upon the breast of the wearer and is provided at its rear with apparel engaging means. A watch case is imposed upon the front of plate 1, said watch case being triangular in form, having the forwardly downward inclined wall 2, the forwardly upward inclined wall 3, and the vertical side walls 4. The watch face 5 lies in a plane that is parallel with the inclined wall 2, so that when the device is in position upon the wearer's breast the time can be easily read upon a slight inclination of the wearer's head.

As will be noted in Figs. 1 and 2 the time indications upon the watch face or dial are oriented with the numeral 12 disposed in the lowermost position, whereby the wearer upon glancing downwardly is enabled to read the time as though a watch with its time indications conventionally disposed was held opposingly, to the vision, in the usual manner.

The crown of the winding stem is indicated at 6, upon the inclined wall 3, near the apex 7 of the triangle formed by walls 2, 3.

It will be noted that the wall 2 is inclined

at an angle of 45° with respect to the surface of base 1, this angle affording full face vision of the dial when the wearer's head is slightly inclined, but obviously this degree of inclination may be varied so long as the angle employed is such as will permit the user to read the time by looking downwardly without being required to shift the position of the watch.

Heretofore breast worn watches exposed their dials outwardly and the wearer, to read the time, must take the watch by hand and turn it toward her eyes, a proceeding that requires the use of suspensory means, and prevents the employment of fixed means of attachment.

By the aid of my improvement a watch can be securely fastened to the apparel, in the manner of a brooch, and yet will always be conveniently readable by the wearer, without other action than that of looking downwardly.

As means for attaching the device to an article of wearing apparel, I may provide a pair of wings 7, each having a pivot 8 mounted in lugs 9 fixed to the rear surface of base 1, said pivots being in parallel relation, and carrying, at adjacent ends, the spur wheels 10. These spur wheels, while closely adjacent, are not in mesh, and the wings 7 may be folded together and swung apart. When folded together the wings 7 may be entered through an eyelet or button hole provided in a garment, and then may be swung out to the extended position shown in Fig. 3, thus positioning the device. Then a pin 11 may be inserted between opposed spurs of the adjacent wheels 10 to thereby lock the wings in their extended position, thus preventing the accidental or unwarranted removal of the device. The pin 11, which has a head 12, is slidable through a lug 13 that is extended from the back of plate 1, said pin having a collar 14, and a spring 15, lying between lug 13 and collar 14, said spring normally urging the pin into its locking position between spurs of the wheels 10.

To remove the device the pin 11 is first released and then the wings will fold together in the act of withdrawal.

Variations within the spirit and scope of my invention are equally comprehended by the foregoing disclosure.

I claim:

- 5 1. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being arranged for reading from above and the lower wall carrying the stem and crown.
- 10 2. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being arranged for reading from above and the lower wall carrying the stem and crown, said base having rearward means for engagement with a garment.
- 15 3. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown.
- 20 4. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 25 5. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 30 6. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 35 7. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 40 8. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 45 9. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.
- 50 10. As a new article of manufacture a time-piece comprising a base, adapted to be imposed vertically upon the wearer's person, and a watch case projecting forwardly from said base, said watch case forming a right angled triangle with the base as its hypotenuse, the upper wall of said triangle containing the dial and lying at a forwardly downward angle, the time indications on said dial being oriented to dispose the numeral 12 in the lowermost position thereon, and the lower wall carrying the stem and crown, said base having rearward means for engagement with a garment.

55 New York, N. Y., March 25th, 1931.
MARCEL D. KRAMER.
